UNITED STATES PATENT OFFICE

157,580

DESK ORNAMENT OR A SIMILAR ARTICLE

Henry G. Frampton, Miami, Fla.

Application May 16, 1949, Serial No. 2,683

Term of patent 7 years

(Cl. D52—7)

To all whom it may concern:

Be it known that I, Henry G. Frampton, a citizen of the United States, residing at Miami, in the county of Dade and State of Florida, have invented a new, original, and ornamental Design for a Desk Ornament or a Similar Article, of which the following is a specification, reference being had to the accompanying drawing, forming part thereof.

Figure 1 is a front perspective view of a desk ornament or a similar article, showing my new design;

The characteristic features of my design reside in the portion shown in full lines.

I claim:

The ornamental design for a desk ornament or a similar article, as shown and described.

HENRY G. FRAMPTON.
